(57) **CLAIM**

The ornamental design for a latch lock, as shown and described.

DESCRIPTION

FIG. 1 is a perspective view of a latch lock showing my new design;

FIG. 2 is a top plan view of the latch lock of FIG. 1;

FIG. 3 is a bottom plan view of the latch lock of FIG. 1;

FIG. 4 is a left side elevation view of the latch lock of FIG. 1; FIG. 5 is a right side elevation view of the latch lock of FIG. 1;

FIG. 6 is a rear elevation view of the latch lock of FIG. 1;

FIG. 7 is a front elevation view of the latch lock of FIG. 1;

FIG. 8 is a perspective view of a latch lock, with a latch shown as being recessed into the casing;

FIG. 9 is a top plan view of the latch lock of FIG. 8;

FIG. 10 is a bottom plan view of the latch lock of FIG. 8; FIG. 11 is a left side elevation view of the latch lock of FIG. 8;

FIG. 12 is a right side elevation view of the latch lock of FIG. 8;

FIG. 13 is a rear elevation view of the latch lock of FIG. 8;

FIG. 14 is a front elevation view of the latch lock of FIG. 8;

FIG. 15 is a perspective view of a latch lock, shown in its environmental use with furniture; and,

FIG. 16 is a perspective view of a latch lock, with the latch lock shown as being engaged with a receiving part.

The broken lines illustrate the unclaimed portions and environment and form no part of the claimed design. The dot-dash lines define the bounds of the claimed design and form no part of the claimed design.

1 Claim, 8 Drawing Sheets
